UNITED STATES PATENT OFFICE.

LOUIS H. WALES, OF NEW BRITAIN, CONNECTICUT, ASSIGNOR TO THE RUSSELL & ERWIN MANUFACTURING COMPANY, OF SAME PLACE.

DESIGN FOR A DOOR-ESCUACHEON.

SPECIFICATION forming part of Design No. 32,317, dated March 6, 1900.

Application filed February 7, 1900. Serial No. 4,404. Term of patent 7 years.

To all whom it may concern:

Be it known that I, LOUIS H. WALES, a citizen of the United States, residing at New Britain, in the county of Hartford and State of Connecticut, have invented and produced a new and original Design for Door-Escutcheons, of which the following is a specification, reference being had to the accompanying drawing, forming part thereof.

The only figure of the drawing is a front elevation of a door-escutcheon, showing my design.

As shown in the drawing, the escutcheon has an oblong rectangular contour and is bordered by a plane band or rib 2. Inside of the said rib there is a series of crosslets 3, parallel to the same. Inside of the series of crosslets and parallel thereto is an inner plane band or rib 4, with curved bands 5 at the four corners, which curved bands meet each other at the ends. At each corner in the triangu-

lar panels formed by the inner band 4 and the curved bands 5 there is a circular figure 6. Inside of the inner band 4 and the curved bands there is another band with inwardly-pointed V-shaped offsets 7. Near the upper end there is a square 8, with the knob-rose 9 thereon. Above the same is a floral ornament 10, and below it is another floral ornament 11, representing a conventional tulip. 25 The ordinary keyhole 12 is formed in a plane surface having a rectangular contour with lateral points at each corner.

30

Having described my invention, what I claim, and desire to secure by Letters Patent, 35 is—

The design for a door-escutcheon, as herein shown and described.

LOUIS H. WALES.
